UNITED STATES PATENT OFFICE.

LUTHER P. JONES, OF RUSSELLVILLE, ALABAMA, ASSIGNOR OF ONE-HALF TO CHARLES WOMBLE, OF FRANKLIN COUNTY, ALABAMA.

SWINGING CRADLE.

1,270,417.

Specification of Letters Patent. Patented June 25, 1918.

Application filed September 30, 1916. Serial No. 123,039.

To all whom it may concern:

Be it known that I, LUTHER P. JONES, a citizen of the United States, residing at Russellville, in the county of Franklin and State of Alabama, have invented certain new and useful Improvements in Swinging Cradles; and I do hereby declare the following to be a full, clear, and exact description of the invention, such as will enable others skilled in the art to which it appertains to make and use the same.

The invention relates to improvements in swinging cradles.

The object of the present invention is to improve the construction of that class of swinging cradles which are actuated by clock mechanism and to provide a simple, practical and comparatively inexpensive construction adapted to firmly mount the clock mechanism upon a supporting frame and capable of securely suspending a cradle and enabling the clock mechanism to actuate the said cradle in the swinging thereof.

Another object of the invention is to provide a swinging cradle of this character adapted to enable a screen to be readily placed over the device without either the clock mechanism or the cradle interfering with the said screen.

With these and other objects in view, the invention consists in the construction and novel combination of parts hereinafter fully described, illustrated in the accompanying drawing, and pointed out in the claims hereto appended; it being understood that various changes in the form, proportion, size and minor details of construction, within the scope of the claims, may be resorted to without departing from the spirit or sacrificing any of the advantages of the invention.

In the drawings—

Figure 1 is a vertical longitudinal sectional view of a swing cradle constructed in accordance with this invention,

Fig. 2 is a transverse sectional view of the same,

Fig. 3 is a detail perspective view of the

clamping member for engaging the clock mechanism, 50

Fig. 4 is a horizontal sectional view illustrating the manner of clamping the frame work of the clock mechanism.

Fig. 5 is a detail view illustrating the construction of the controlling means for holding the cradle against movement.

Like numerals of reference designate corresponding parts in the several figures of the drawings.

In the accompanying drawings in which is illustrated the preferred embodiment of the invention, the device comprises in its construction a supporting frame preferably composed of corner posts or legs 1 and top, side and end bars 2 and 3. The legs which are equipped with rollers are preferably connected between their ends by rungs or braces 4 but any other suitable bracing means may of course be employed as will be readily understood. The legs which are preferably inclined slightly as shown are of a sufficient length and are spaced apart a sufficient distance to permit a cradle 5 to oscillate beneath the top of the frame formed by the said side and end bars 2 and 3. The cradle 75 which may be of any desired construction is preferably connected with and suspended from an oscillatory arm or member 6 by arched or looped flexible connections 7 and 8 extending diagonally of the cradle over 80 the top of the same and connected intermediate of their ends with upper and lower hooks 9 and 10 carried by the oscillatory arm or member 6, but the cradle may be suspended from the same in any other desired 85 manner. The oscillatory arm or member 6 which may be mounted in any desired manner is shown in the accompanying drawings as consisting of a resilient rod or bar secured at the upper end 11 to the frame work 90 12 of clock mechanism 13 having an escapement connected with and adapted to actuate the oscillatory member 6. The oscillatory member 6 cooperates with the escapement which includes an escapement wheel 95 14 and an escapement lever 15 of the ordi-

nary construction. The clock mechanism, which, in practice will be of sufficient strength to swing the cradle is designed to be provided with a controlling device comprising a shaft 16 having an operating head 17 and provided with an arm 18 arranged to engage the escapement wheel for holding the same against movement.

The frame work of the clock mechanism or spring motor comprises spaced rear and front corner standards 19 and 20, the front corner standard 20 being supported upon a transverse bar or member 19 of the supporting frame and the rear legs of standards 20 being engaged by a clamp 22 suitably mounted on a transverse bar or member 23 and provided with end recesses 24 and having a top longitudinal slot 25 receiving the rear standards 20 as clearly illustrated in Fig. 4 of the drawings. The end recesses form shoulders which engage horizontal rods 26 connecting the front and rear standards 19 and 20. The longitudinal slot 25 forms opposite clamping portions or jaws 27 which are connected by screws 28 adapted to be tightened to cause a sufficient binding of the jaws 27 to firmly grip the rear legs or standards 20 of the frame work 12 to securely hold the spring motor in proper position on the supporting frame.

The longitudinal slot 25 extends through the recessed terminal portions of the clamp and forms grooves 25^a which receive the ends 35 of the rear legs or standards and permit the legs or standards to drop sufficiently to allow the horizontal rods to rest upon the recessed ends of the clamp. By this construction the rear legs and the rods support the motor and 40 the latter is firmly interlocked with the clamp. The bar 21, which is arranged in parallelism with the clamping bar 22, is provided with a longitudinal slot 21^a and it has terminal recesses 24^a, the longitudinal slot 45 being extended through the recessed terminals of the bar 21 similar to the longitudinal slot of the clamping bar. It is only necessary to provide the clamping screws 28 at the clamping bar as the jaws formed by the 50 longitudinal slot of the clamping bar will firmly hold the frame of the motor in its superimposed position with relation to the supporting frame.

The spring motor is designed to be 55 equipped with a suitable crank 29 for winding the spring and the mechanism of the motor is preferably protected by a casing 30 of approximately rectangular form suitably mounted on the supporting frame and 60 adapted to prevent a screen 31 of mosquito netting or other material from coming in contact with the clock mechanism or motor.

The open frame which is comparatively light, spaces the protecting screen or covering from the cradle. The screen or covering 65 may be removed when not required.

What is claimed is:—

1. A device of the class described including a rectangular supporting frame disposed horizontally and provided at the corners with supporting legs, a motor mounted upon the supporting frame and projecting upwardly beyond the same and having a casing, a cradle located beneath the supporting frame and connected with and actuated by the motor and suspended from the same, and a screen covering extending over the supporting frame and the motor casing and inclosing the legs of the said supporting frame. 75

2. A device of the class described including a supporting frame, a motor mounted upon the supporting frame, an oscillatory member depending from the motor and provided with upper and lower hooks arranged in spaced relation, a cradle provided with 80 diagonally arranged flexible connections of unequal length connected with the corners of the cradle and suspended at an intermediate point from the spaced hooks, the shorter flexible connection extending through the 85 longer flexible connection, and means actuated by the motor and connected with the oscillatory member for actuating the latter.

3. The combination with a supporting frame, of a bar extending across the supporting frame and having terminal recesses and provided with a longitudinal slot extending through the recessed portions of the bar, a motor located above the frame and provided with spaced legs and rods connecting the 100 legs, two of the legs being arranged in the said slot and the rods being located in the recesses to prevent movement of the legs longitudinally of the slot, and a cradle located beneath and suspended from the 105 motor.

4. The combination with a horizontal open supporting frame, transverse bars extending across the supporting frame in parallelism and having recessed ends and provided with longitudinal slots extending through the recessed terminals of the bars, a motor having a frame provided with legs and connecting rods, the legs being arranged in the said slots and the rods fitting in the 110 recesses and holding the legs against movement longitudinally of the said slots, and clamping screws mounted on one of the said bars and extending across the longitudinal slot for causing such bar to clamp the legs, 115 and a cradle located beneath the open supporting frame and suspended from the motor.

5. The combination with a supporting

frame, of parallel bars mounted thereon in spaced relation and having recessed terminals forming shoulders and provided with longitudinal slots extending through the 5 terminals of the bars, and a superimposed motor frame provided with legs and connecting rods, the legs being arranged in the slots and the rods fitting against the shoulders formed by the recesses, and clamping means

mounted on one of the bars and extending 10 across the slot thereof for causing the slotted portions of the said bar to clamp the legs.

In testimony whereof I affix my signature in presence of two witnesses.

LUTHER P. JONES.
